Primary Examiner — Nathan M Johnston(74) *Attorney, Agent, or Firm* — Liang Legal Group,
PLLC**(57) CLAIM**

The bench vise, as shown and described.

DESCRIPTION

FIG. 1 is a front elevation view of a bench vise showing our new design;

FIG. 2 is a rear elevation view thereof;

FIG. 3 is a left side elevation view thereof;

FIG. 4 is a right side elevation view thereof;

FIG. 5 is a bottom plan view thereof;

FIG. 6 is a top plan view thereof;

FIG. 7 is a perspective view thereof; and,

FIG. 8 is another perspective view thereof.

The broken lines show portions of the design that form no part of the claimed design.

1 Claim, 8 Drawing Sheets(56)
